Primary Examiner—Nelson C. Holtje*Attorney, Agent, or Firm*—Freilich Hornbaker Rosen**[57] CLAIM**

The ornamental design for combined clock and thermometer housing, as shown and described.

DESCRIPTION

FIG. 1 is a front isometric view of a combined clock and thermometer housing showing my new design;

FIG. 2 is a front elevation view thereof, the broken line showings of hands being illustrative of environment only and forming no part of the claimed design;

FIG. 3 is a top elevation view thereof with the bottom view being identical;

FIG. 4 is a rear elevation view thereof; and,

FIG. 5 is a right side elevation view thereof, with the left side elevation view being identical.
